UNITED STATES PATENT OFFICE.

ROBERT M. DYER AND LA VERNE W. NOYES, OF CHICAGO, ILLINOIS,
ASSIGNORS TO THE AEROMOTOR COMPANY, OF SAME PLACE.

WINDMILL.

SPECIFICATION forming part of Letters Patent No. 608,657, dated August 9, 1898.

Application filed August 5, 1897. Serial No. 647,151. (No model.)

To all whom it may concern:

Be it known that we, ROBERT M. DYER and LA VERNE W. NOYES, citizens of the United States, residing at Chicago, in the county of Cook and State of Illinois, have invented a certain new and useful Improvement in Windmills, of which the following is a full, clear, concise, and exact description, reference being had to the accompanying drawings, forming a part of this specification.

Our invention relates to a windmill, our object being to provide an improved mechanism for furling the mill and throwing on and off the brake.

15 In accordance with our invention the tail of the mill is connected with a furling-lever which acts to lock the tail in position when out of the wind and which is resiliently pressed to start the tail in its movement when 20 being thrown out of the wind. The furl-lever also controls the brake, throwing the brake on when the tail is out of the wind and off when the tail is in the wind.

Referring to the accompanying drawings, 25 Figure 1 is a plan view of the mill equipped with our invention. Fig. 2 is a view in elevation. Fig. 3 is a plan view showing the different positions of the furling and braking mechanism. Fig. 4 is a detached view 30 of the tail and furl-lever. Fig. 5 is a detail view of the rollers which guide the furling-chain.

Like letters refer to like parts in the several figures.

35 The tail-bone a is pivoted upon the frame b at a' and is connected by the coiled spring a^2 with the arm c' of the furl-lever c , pivoted upon the frame b at c^2 to one side of the pivot of the tail-bone. To the arm c^3 of the furl-lever is secured the furling-chain c^4 , which 40 passes around the flanged roller c^5 and over the roller c^6 and down through the barrel of the frame. The furl-lever carries an arm c^7 , adapted to engage the bent end d' of rod d , which passes through an opening in the lug or bearing b' of the frame and is secured at the opposite end to the brake disk or shoe e , having a beveled periphery adapted to engage a correspondingly-beveled flange f' on 45 the wind-wheel f . The rod d is bent where the same passes through the opening in lug 50

b' , so that as the end d' of the rod moves in the arc of a circle due to its engagement by the arm c^7 of the pivoted furl-lever the rod will pass through the opening in the lug without binding. The rod is thus bent so that it is substantially coincident with the line of motion of the rod d where the same passes through the bearing. The brake-shoe carries a pair of downwardly-extending arms $e' e'$, 55 which straddle the bearing-sleeve b^2 on the frame to prevent the rotation of the brake-shoe. A coiled spring g surrounds the rod d and rests between the shoulder d^2 thereon and the lug b' to thus resiliently impart to 60 the rod d a tendency to move toward the wind-wheel to throw on the brake. Upon the under face of the arm c' of the furl-lever is provided a lug c^8 , which bears against the edge or side of the tail-bone a , to thereby impart 65 to the tail-bone a tendency to move out of the wind, due to the effect of the spring g tending to rotate the furl-lever. As the tail-bone and furl-lever rotate the lug c^8 travels 70 along the edge of the tail-bone, due to the fact that the pivot of the furl-lever is different from that of the tail-bone, and when the tail-bone occupies the position shown in dotted lines the lug c^8 enters the notch a^3 in the edge of the tail-bone, thus locking the 75 tail-bone in position out of the wind. Any pressure brought to bear against the tail is unable to move the tail, because it is resisted by the arm c' of the furl-lever. By means of the chain c^4 , however, the lug c^8 is moved out 80 of the notch a^3 , and the tail is thus unlocked and is swung into the wind by the movement of the furl-lever acting upon the tail-bone through the spring a^2 . Instead of employing 85 the interlocking device in the form of a lug and notch any form of interlocking device may be employed which will serve to lock 90 the tail in position out of the wind.

The resiliently-pressed furl-lever may be otherwise arranged to start the tail in its 95 movement out of the wind, the only requisite being that the movement of the furl-lever shall act upon the tail to impart an initial movement thereto. The detailed construction illustrated we have found to give the 100 desired effective operation. Instead of resiliently pressing the furl-lever by a spring,

equivalent means, as a weight, may be employed.

The spring *g* besides acting to start the tail when moving out of the wind also serves to throw on the brake, the furl-lever serving to retract the brake against the tension of the spring when the furl-lever is rotated by the chain *c*⁴, and the arm *c*⁷ thereby caused to engage and retract the rod *d*.

10 With the parts in the position illustrated in full lines in Fig. 3 the tail is held in the wind, and the brake is off. To throw the mill out of the wind, the chain *c*⁴ is released, and the spring *g* acts upon the arm *c*⁷ to rotate the furl-lever and swing the tail through the engagement of the lug *c*⁸ with the edge of the tail-bone. The spring *g* acts at the same time to move the brake-shoe *e* into engagement with the flange *f*' on the wheel, and when the lug *c*⁸ engages the notch *a*³ the tail is locked in position out of the wind. In throwing the mill into the wind the furl-lever is rotated by the chain *c*⁴ to unlock the tail and move the tail into the wind, and the arm *c*⁷ engages the end of the rod *d* to place the spring *g* under tension and to move the brake-shoe *e* out of engagement with the flange *f*' on the wheel.

Having described our invention, what we claim as new, and desire to secure by Letters

30 Patent, is—

1. A hinged tail for a windmill, and a furl-lever pivoted upon the frame or turn-table and connected with the tail and arranged to interlock therewith when the mill is out of the wind, substantially as described.

2. A hinged tail for a windmill and a furl-lever pivoted eccentric thereto and connected with said tail and arranged to interlock therewith when the mill is out of the wind, substantially as described.

3. A hinged tail for a windmill and a furl-lever pivoted eccentric thereto and carrying a lug arranged to engage a notch upon the tail when the mill is out of the wind, substantially as described.

4. A hinged tail for a windmill, a furl-lever pivoted upon the frame or turn-table and connected therewith, and means, as a spring, for resiliently pressing said furl-lever in a direction to start the tail out of the wind, substantially as described.

5. A hinged tail for a windmill, a furl-lever pivoted upon the frame or turn-table and connected therewith, a resilient connection, as a coiled spring, between the furl-lever and the tail, and means as a spring for resiliently pressing said furl-lever in a direction to start the tail out of the wind, substantially as described.

6. A hinged tail for a windmill, a resiliently-pressed furl-lever, a resilient connection, as a coiled spring, between the furl-lever and the tail, said furl-lever being arranged to start the tail out of the wind, and an in-

terlocking device arranged to interlock the furl-lever and the tail when the tail is out of the wind, substantially as described.

7. A hinged tail for a windmill and a resiliently-pressed furl-lever pivoted eccentric thereto, connected therewith and arranged to start the same out of the wind and arranged to interlock with the tail when the mill is out of the wind, substantially as described.

8. A hinged tail for a windmill, and a resiliently-pressed furl-lever pivoted eccentric thereto, connected therewith and having a lug engaging and moving along the tail and arranged to enter a notch or recess on the tail to lock the same when the mill is out of the wind, substantially as described.

9. A hinged tail for a windmill, a resiliently-pressed furl-lever pivoted eccentric thereto and having a lug engaging and moving along the tail and arranged to enter a notch or recess on the tail when the mill is out of the wind and a coiled spring between the furl-lever and the tail, substantially as described.

10. The hinged tail, the furl-lever pivoted eccentric thereto, having the arm *c*' resiliently connected with the tail and carrying the lug *c*⁸ arranged to enter the notch *a*³, the operating-arm *c*³ and the arm *c*⁷, and the spring-pressed rod *d* adapted to be engaged by said arm *c*⁷, substantially as described.

11. The hinged tail, the furl-lever pivoted eccentric thereto, having the arm *c*' resiliently connected with the tail, and carrying the lug *c*⁸ arranged to enter the notch *a*³, the operating-arm *c*³ and the arm *c*⁷, the spring-pressed rod *d* adapted to be engaged by said arm *c*⁷ and the brake-shoe connected to said rod, substantially as described.

12. The combination with a brake-shoe, of a spring to move the same to brake the wheel, a pivoted tail and a pivoted furl-lever for swinging said tail and connected with said brake-shoe to retract the same against the tension of said spring when the mill is swung into the wind, substantially as described.

13. The combination with the brake-shoe and the rod connected therewith, of a spring surrounding said rod to press the shoe to brake the wheel, a pivoted tail and a pivoted furl-lever for swinging said tail and having an arm arranged to engage said rod to retract the brake-shoe against the tension of the spring when the mill is swung into the wind, substantially as described.

In witness whereof we have hereunto subscribed our names in the presence of two witnesses.
